INVENTOR:

Norman T. Thomas,
By his attorney,
J. S. McCrory.

UNITED STATES PATENT OFFICE.

NORMAN T. THOMAS, OF NASHUA, NEW HAMPSHIRE, ASSIGNOR TO NASHUA MANUFACTURING COMPANY, OF NASHUA, NEW HAMPSHIRE, A CORPORATION OF NEW HAMPSHIRE.

CLOTH-INSPECTING MACHINE.

Application filed October 15, 1923. Serial No. 668,510.

To all whom it may concern:

Be it known that I, NORMAN T. THOMAS, a citizen of the United States, residing at Nashua, in the county of Hillsborough and State of New Hampshire, have invented certain new and useful Improvements in Cloth-Inspecting Machines, of which the following is a specification.

After the manufacturing operations on cloth have been substantially completed, it is customary to inspect the fabric for flaws and imperfections. The present invention relates to apparatus used in performing this inspecting operation, and it has for its chief object to improve such apparatus with a view especially to improving the accuracy of inspection, reducing the labor involved, and simplifying the introduction of a new web of cloth into the apparatus in readiness for the inspecting operation.

In the forms of cloth inspection apparatus now in common use, the operation of initially threading in a new web of cloth in readiness for inspection is very difficult. It is the custom, therefore, to perform this threading-in operation by fastening the trailing end of the web which is just running out to the end of the new web, and thus use the motion of the web already in the apparatus to draw in the new web. The fact, however, that the introduction of the web, unless performed in this particular manner, is very difficult, causes an inspector to watch the roll of cloth from which the web is being drawn very carefully as the end is approached to make sure that the end will not run out before she can piece on the end of a new web. This takes her attention from the cloth, with the result that the inspection becomes inaccurate. The present invention provides an apparatus which is not open to this objection.

An especially important feature of the invention resides in a novel arrangement for supporting webs of cloth in readiness for delivery to the machine, and in the arrangement for effecting such delivery.

The nature of the invention will be readily understood from the following description when read in connection with the accompanying drawings, and the novel features will be particularly pointed out in the appended claims.

Referring now to the drawings,

Figure 1 is a perspective view of part of a cloth inspecting apparatus constructed in accordance with this invention;

Fig. 2 is a plan view partly in cross section of the apparatus shown in Fig. 1;

Fig. 3 is a cross sectional diagram of a part of the apparatus; and

Fig. 4 is a diagrammatic view of the driving roll and adjacent parts.

The apparatus shown comprises an inspection stand which includes frame pieces 2 and 3 and an inclined board 4 supported by said frame pieces. A web of cloth C to be inspected is unwound from a supply roll 5 which is supported in a cradle 6 mounted immediately below the board 4. This web of cloth passes directly from the supply roll 5 to a guide roll 7 at the lower edge of the board 4, thence over the board and between a driving roll 8 and a weighting roll 9 to a guide roll 10, Fig. 3. The web is rolled up again at 12 on the usual tube or pipe core which rotates on a shell roll 14.

The driving mechanism for the rolls 8 and 14 may be exactly like that employed in the cloth inspecting machines at present in common use. The shaft of the roll 8 carries a loose pulley 15, Fig. 4, which is belted directly to some convenient source of power. A clutch, one member of which is indicated at 16 in Fig. 4, is splined to the roll shaft and is slidable to connect or disconnect the shaft with the pulley, this clutch being under the control of a treadle 17 (Figs. 1 and 2). A spring (not shown) acts on the connections between this treadle and the clutch element 16 to hold the clutch normally out, or to disconnect it from the pulley, so that the inspector must hold the treadle 17 depressed in order to keep the cloth feeding over the stand. As soon as the treadle is released, the rotation of the roll 8 is stopped, and consequently the cloth feeding movement is stopped.

Another mechanism which need not be described here, is provided to drive the roll 8 in a reverse direction to effect a backward feed of the cloth, this mechanism being under the control of the treadle 18 (Figs. 1 and 2).

The shaft of the shell roll 14 carries a pulley 19 which is driven by a belt 20 from

another pulley 21 fast on the shaft of the roll 8.

For the purpose of facilitating the delivery of a new roll of cloth to the cradle 6, a stand or platform 24 is located in front of the inspecting stand 4, and is of sufficient dimensions to support several spare rolls 25. The top of this platform is slightly inclined toward the stand so that the rolls tend to roll toward the cradle, and the foremost roll is stopped by a bevelled strip 26 located near the front of the platform. Two rails 27-27 connected at their ends by pieces 28-28 are mounted to slide just under the top of the platform, the rails being supported on strips, one of which is shown at 29 (Fig. 1), so that they may be moved forward into the dotted line position shown in Fig. 2, with the front cross piece 28 resting on the topmost roll of the cradle 6. In this position they bridge the space between the platform and the cradle so that it is a very easy matter for the inspector then to push the front roll 25 over the stop 26, after which it will roll by gravity on the rails 27-27 into the cradle 6. When this transfer or delivery of a new roll to the cradle has been completed, the inspector slides the rails 27-27 back under the platform where they are out of the way. A hole 37, Fig. 2, is cut in the top of the platform near its forward edge to afford convenient access to the front cross piece 28.

A chair or seat 30 is provided for the inspector, and is supported on a bracket 31 which is pivoted at 32 on a vertical stand or base 33, so that the seat can be swung from its normal position in front of the inspecting stand into an inoperative position, as shown in dotted lines in Fig. 2, at one side of the path of delivery of the rolls 25.

In some machines considerable pressure must be exerted on the treadle 17 in starting the machine into operation, and in order to enable the inspector to exert the desired pressure more easily and comfortably, an arm 34 (Fig. 1) is secured to the seat 30, and is bent downwardly so that when the seat is pushed back away from the table, this bracket will engage the front of the platform 24 and act as a stop. This arrangement enables the inspector to brace against the back of the chair as she depresses the treadle 17. The seat also is adjustable vertically to the requirements of different inspectors. For this purpose the seat is mounted on a screw 35 which is threaded in a hole formed in the outer end of the bracket 31, and a set screw 36 is provided to lock the screw 35 in its adjusted position.

After the inspection of a web of cloth has been completed, and the end of the web appears on the board 4, the inspector transfers a new roll to the cradle 6 as above described, she then pulls the end of the web

of cloth from this roll up on the table and pins it to the trailing end of the web which is just running out. This operation can be performed very conveniently and with a minimum of effort, for the reason that no threading-in of the end is required, it being simply necessary to pick up the end of the web on the roll in the cradle and pull it over the guide roll 7 and lay it on the table 4. The inspector next depresses the treadle 17 to start the feeding of the web, so that the new end will be carried through the rolls 8 and 9 into position to be wound on a tube or pipe 12 which will be placed by an attendant in the proper position on the shell roll 14.

It will be evident to those skilled in this art that in using this apparatus there is no occasion for the uneasiness which inspectors now experience lest the end of the web run out. The inspector's attention can be confined entirely to the cloth until the end of the web appears on the table or stand 4. The inspector then releases the treadle 17, thus stopping the feeding of the cloth, and transfers a new roll to the cradle in the manner above described. This apparatus, therefore, results in a more careful and accurate inspection of the cloth, and it eliminates the difficulty in threading-in which has been experienced in apparatus of this type heretofore used.

The fact that one or more spare rolls of cloth are always on the platform ready to be delivered to the cradle, and the ease with which this delivery is effected are important factors in eliminating delay in changing rolls, and hence increase the output of the machine.

It will also be appreciated that while I have herein shown and described the best embodiment of my invention that I have so far devised, the invention may be embodied in many other forms without departing from the spirit or scope thereof. For example, the platform and cradle may be replaced by equivalent pieces of apparatus performing essentially the same functions but differing in minor details, and these terms are intended to include equivalent structures.

Having thus described my invention, what I desire to claim as new is:

1. In a cloth inspection apparatus, the combination of an inspecting stand, mechanism for feeding a web of cloth over said stand, a cradle for supporting a roll of cloth from which said web is unwound in a position under said stand, a platform in front of said stand for supporting a plurality of said rolls, rails for supporting said rolls for delivery from said platform to said cradle, a seat normally positioned in front of said stand, and means at one side of the path of delivery of said rolls for supporting said seat.

2. In a cloth inspection apparatus, the combination of an inspecting stand, mechanism for feeding a web of cloth over said stand, a cradle for supporting a roll of cloth from which said web is unwound in a position under said stand, means in front of said stand for supporting a roll in readiness for delivery to said cradle, a seat normally positioned in front of said stand, a bracket supporting said seat, and a pivotal support for said bracket at one side of the path of delivery of said roll, whereby said seat may be swung into and out of its operative position.
3. In a cloth inspection apparatus, the combination of an inspecting stand, mechanism for feeding a web of cloth over said stand, a cradle for supporting a roll of cloth from which said web is unwound in a position under said stand, a platform in front of said stand for supporting a plurality of said rolls, rails for supporting said rolls for delivery from said platform to said cradle, a seat normally positioned in front of said stand, a bracket pivotally mounted at one side of the path of delivery of said rolls and supporting said seat for swinging movement into and out of its normal position, and a rigid arm movable with said seat and positioned for engagement with the front of said platform when the seat is in its normal position.
4. In a cloth inspection apparatus, the combination of an inspecting stand, mechanism for feeding a web of cloth over said stand, a cradle for supporting a roll of cloth from which said web is unwound, a platform in front of said stand for supporting a plurality of said rolls in readiness for delivery to said cradle, and rails movable into and out of operative position for supporting said rolls for delivery from said platform to said cradle.
5. In a cloth inspection apparatus, the combination of an inspecting stand, mechanism for feeding a web of cloth over said stand, a cradle for supporting a roll of cloth from which said web is unwound, a platform in front of said stand for supporting a plurality of said rolls, rails for supporting said rolls for delivery from said platform to said cradle, means for supporting said rails under said platform for sliding movement into position to bridge the space between said platform and said cradle, a seat normally positioned in front of said stand, and means at one side of the path of delivery of said rolls for supporting said seat.
6. In a cloth inspection apparatus, the combination of an inspecting stand, mechanism for feeding a web of cloth over said stand, a cradle for supporting a roll of cloth from which said web is unwound in a position under said stand, means in front of said stand for supporting a roll in readiness for delivery to said cradle, a seat normally positioned in front of said stand, and means at one side of the path of delivery of said roll for supporting said seat.

NORMAN T. THOMAS.
